FORM-RAISING JACK

Anthony P. Wiertz, Dayton, Ohio

Application June 3, 1943, Serial No. 489,520

5 Claims. (Cl. 254—120)

The invention relates to a jack mechanism primarily adapted for use in raising concrete forms.

It is particularly aimed to provide a novel construction to coact with a rod upon which it may be operated to climb, which rod functions also as a reinforcement for poured concrete.

In addition it is aimed to provide a novel means which will prevent slippage of the mechanism downwardly on the rod mentioned, and a construction wherein the yoke or biting parts are maintained under tension in order to bite or directly engage the rod at all times.

The more specific objects and advantages will become apparent from a consideration of the description following taken in connection with accompanying drawings illustrating an operative embodiment.

In said drawings:

Figure 1 is a view illustrating my improvement in elevation and in connection with a concrete form partly shown in elevation and partly in section;

Figure 2 is a view in elevation of my improvement taken at a right angle to Figure 1;

Figure 3 is a view in elevation of my improvement alone, looking in the same direction as Figure 1, but partly broken away;

Figure 4 is a view of my improvement taken at a right angle to Figure 3, and with most parts in substantially central longitudinal section; and

Figure 5 is a plan view of one of the yokes.

Referring specifically to the drawings wherein like reference characters designate like or similar parts, I employ a mount generally designated 10, having a basal flange at 11 and a hollow frustal conical portion 12 whose larger dimension is lowermost.

The base flange 11 is adapted to be fastened in a horizontal plane in any suitable manner to a concrete form 13, for instance, which is adapted to be lifted through the operation of my improved jacking mechanism. The form 13 employs one or more parts 14, in or between which the concrete is adapted to be poured, and in or between which a rod 15 is vertically disposed, for the improved jacking mechanism to climb on, in order to raise the form. At the same time, it is to be understood that the jacking mechanism is capable of more general use and that its employment in connection with concrete form structures is but one illustration of its use.

It will be noted that the rod 15 extends upwardly and centrally through the frustal portion 12. An operating lever having a part 16 generally of U shape is pivotally mounted by suitable bolt

means or trunnions 17 on the conical part 12 and from which a suitable handle 18 projects.

A pair of yokes 19 are disposed at opposite angles, and the rod 15 passes through the same. Said yokes have vertical links 20 disposed on opposite sides of the rod with their upper ends at 21, pivotally connected to the yokes 19; and their lower ends 22 pivotally connected to the operating lever at the U-shaped portion 16. Thus it will be seen that the operation of the lever 16—18 will result in the jack's climbing or progressively ascending along the rod 15 and carrying with it the form 13 and all parts attached to it, permitting use of the form 13 at different elevations, as the pouring of concrete into or between the part or parts 14 progresses.

In lieu of the yokes 19 directly engaging or biting the rod 15 at an edge thereof, biting lugs 23 are provided on the yokes for direct biting action for engagement with the rod. Said lugs or bars 23 preferably are of relatively hard metal and are removable and replaceable, simply being held in place by driving them into and out of openings of approximately their own shape and size in the yokes. This type of mounting also enables the lugs 23 to be driven by a hammer into different positions of adjustment to provide an effective biting edge when they become worn. In addition, such lugs may be of any desired cross-sectional area, preferably being polygonal as shown, so that they may be removed, and any of the plurality of edges shown be brought into position to engage the rod.

To enhance the biting effect and to maintain the lugs in engagement with the rod, contractile coil springs are employed at 24 across the joint or knuckle of the yokes 19 and links 20, being detachably connected to hooks 25 and 26, on such parts, respectively.

I also provide a safety means to prevent downward slippage or displacement of the jacking mechanism on the rod 15, which may consist of two or more slips or wedges 27, the same being separable from each other and collectively of the same shape as the space between the inner wall of the frustal portion 12 and outer wall of the rod 15. Said slips 27 are held in place and urged upwardly by spring fingers at 28, fastened at 29 to the under surface of the basal flange 11. It will be realized that the wedges or slips 27 do not interfere with the raising of the jack and form on the rod 15 through operation of the lever 16—18, but in the event that the lugs 23 should fail to catch or bite the rod and there is danger of downward slippage, the slips or wedges 27 will

wedge between the part 12 and rod in order to hold the form and jacking mechanism in place.

Attention is called to the fact that the rod 15 remains permanently in the poured concrete to function dually as a reinforcement therefor as well as a means on which the jack climbs.

Various changes may be resorted to provided that they fall within the spirit and scope of the invention.

I claim as my invention:

1. Jack mechanism of the class described comprising a mount for attachment to a part to be lifted, said mount being open so that a rod may extend through and above the same, lever means pivoted on the mount, and oppositely operable yokes disposed to bite the rod at opposite sides through the manipulation of the lever to cause the jack to climb the rod, and wedge means retained by the mount to wedge between the same and the rod to avoid lowering of the mount on the rod.

2. Jack mechanism of the class described comprising a mount for attachment to a part to be lifted, said mount being open so that a rod may extend through and above the same, lever means pivoted on the mount, and oppositely operable yokes disposed to bite the rod at opposite sides through the manipulation of the lever to cause the jack to climb the rod, and wedge means retained by the mount to wedge between the same and the rod to avoid lowering of the mount on the rod, said wedge means consisting of a plurality of wedge-shaped parts, the mount having a conical portion in which the wedge-shaped parts are disposed, and spring means on the mount to retain said wedge members thereon.

3. Jack mechanism of the class described comprising a mount for attachment to a part to be lifted, said mount being open so that a rod may extend through and above the same, lever means pivoted on the mount, and oppositely operable

yokes disposed to bite the rod at opposite sides through the manipulation of the lever to cause the jack to climb the rod, and wedge means retained by the mount to wedge between the same and the rod to avoid lowering of the mount on the rod, said wedge means consisting of a plurality of wedge-shaped parts, the mount having a conical portion in which the wedge-shaped parts are disposed, and spring means on the mount to retain said wedge members thereon, said yoke members having adjustable biting elements to engage the rod, links pivoted to the lever and to the yokes, and contractile coil springs connected to the yokes and the links urging said elements to biting engagement with the rod.

4. Jack mechanism of the class described comprising a mount for attachment to a part to be lifted, said mount being open so that a rod may extend through and above the same, lever means pivoted on the mount, and oppositely operable yokes disposed to bite the rod at opposite sides through the manipulation of the lever to cause the jack to climb the rod, said yokes having adjustable biting elements providing a plurality of edges for selective engagement with the rod.

5. Jack mechanism of the class described comprising a mount for attachment to a part to be lifted, said mount being open so that a rod may extend through and above the same, lever means pivoted on the mount, and oppositely operable yokes disposed to bite the rod at opposite sides through the manipulation of the lever to cause the jack to climb the rod, said yokes having adjustable biting elements providing a plurality of edges for selective engagement with the rod, links pivotally connected to the yokes and to the lever, and contractile coil springs fastened to the yokes and links to maintain the elements in engagement with the rod.

ANTHONY P. WIERTZ.
